UNITED STATES PATENT OFFICE.

CHRISTEN J. PETERSON, OF CHICAGO, ILLINOIS, ASSIGNOR TO CHICAGO FILING MACHINE COMPANY, OF CHICAGO, ILLINOIS, A CORPORATION OF ILLINOIS.

FILING-MACHINE.

No. 388,651.

Specification of Letters Patent.

Patented May 26, 1908.

Application filed October 3, 1907. Serial No. 390,736.

To all whom it may concern:

Be it known that I, CHRISTEN J. PETERSON, a citizen of the United States, residing at Chicago, in the county of Cook and State of Illinois, have invented certain new and useful Improvements in Filing-Machines, of which the following is a specification.

This invention relates more particularly to filing machines of the size and character adapted to be used on a work bench; and the object of the present invention is to so construct the machine that it will be sufficiently compact in form to adapt it for bench usage and at the same time sufficiently strong and rigid to withstand the strain of hard usage.

Another object of the invention is to so construct and arrange the socket for the tang of the file that the file can be easily adjusted and rigidly clamped regardless of the taper or configuration of the tang.

The invention further relates to the means employed for adjusting and holding the upper end of the file; to the mechanism for reciprocating the file blade; and to the clutch mechanism for regulating the power transmission.

The invention further consists in the features of construction and combination of parts hereinafter described and claimed.

In the drawings, Figure 1 is a side elevation of the entire machine; Fig. 2 a longitudinal sectional elevation of the same; Fig. 3 a front elevation; Fig. 4 an enlarged sectional detail of the file tang socket and reciprocating mechanism; Fig. 5 a cross sectional view of the vertical guideways; and Fig. 6 an edge elevation of the slotted driving wheel.

The machine comprises a bed plate 7, adapted to be secured to the top of a bench or similar structure, which bed plate is provided, at its forward end, with an upright framework 8, comprising vertical posts 9, provided at their lower ends with feet 10, which are secured to the bed plate by means of bolts 11 or in any other suitable manner. The posts are beveled on their inner edges 12, and each of the posts has secured to its inner face a vertically extending bar 13, which overlies the beveled inner edge of the post and forms, in combination therewith, a V-shaped guideway. Between the two guideways thus formed is mounted a recip-

rocating frame 14, which comprises vertical side rails 15, the edges of which are beveled to conform to the bevel of the guideways within which they travel. The side rails are connected by lower and upper cross guide rails 16 and 17, respectively, and above the upper cross guide rail is a top socket rail 18 which, in its center, is provided with a recess 19, for the reception of the end of the file tang. The socket rail is reinforced and supported adjacent to the recess 19 by means of vertical posts 20, upwardly extending from the upper cross guide rail. The whole frame thus formed is adapted to reciprocate up and down between the vertical posts and serves to reciprocate the file carried thereby. The socket rail 18 has cast or otherwise formed thereon a rectangular socket block 21, which rearwardly extends from the top of the socket rail and is provided, in its front face, with a rectangular recess 22, in front of which recess is a plate 23, which is secured to the front face of the socket block by means of screws 24, or similar attaching means. The sides of the socket block adjacent to the recess therein, are provided with rearwardly extending slots 25, as shown in Fig. 2; and within the socket recess is located a tilting block 26, having beveled rear faces 27, as shown in Fig. 4.

The tilting block is provided, at its sides, with outwardly extending trunnions 28, adapted to enter the slots 25 provided therefor, and the tilting block is intended to cooperate with the cross plate 23, in providing a socket for the reception of the file tang 29. In view of the fact that tangs of files are ordinarily tapered and of varying size and shape, it is necessary to provide suitable means for rigidly clamping the tang in such position that the file will extend in absolute alignment with the surface sought to be abraded. Such means are provided by a pair of clamping thumb screws 30, which are entered through the plate 23 and are adapted to clamp the file tang against the tilting block on opposite sides of the ridge afforded by the angle of the beveled rear faces of said block. Such ridge forms in effect a fulcrum which bears against the rear face of the recess in the socket block.

The socket block has secured to its rear face a rearwardly extending arm 31, pre-

vided in its end with an upturned socket head 32, into which head is entered a vertically extending rod 33, which has slidably mounted thereon a forwardly extending bracket arm 34, the rear end of which embraces the vertically extending rod 33 and is adapted to be clamped thereon by means of a set screw 35. The end of the forwardly extending arm has entered thereinto an extensible rod 36, which rod is adapted to be clamped in adjusted position by means of a thumb screw 37. The rod carries on its forward end a head 38, provided with a vertical slot 39, which is adapted to receive the upper end of the file blade 40, which latter is clamped within the slot 39 by means of a thumb screw 41 in the head 38.

The upright posts 8 serve as a support for a circular table 42, provided with depending ears 43, through which are entered pivots 44, which serve to pivot the table to the upper ends of the upright posts of the frame and adapt it to be tilted to different angles. In order to clamp the table in the desired position, a set screw 45 is entered through one of the ears and bears against the upper face of the post, so that when tightened the table will be clamped and held in suitable position.

The upper and lower guide bars 16 and 17 of the reciprocating frame 14 serve as a mounting for a transversely reciprocating block 46, provided with guide flanges 47, adapted to bear against the rear edges of the upper and lower guide bars. The block 47, shown in Fig. 4, has entered therethrough a crank pin 48, which is surrounded by a bearing collar 49 of hardened steel. The crank pin is provided with a flange 50, which bears against the rear face of the transversely reciprocating block, and to the rear of the flange the pin is provided with screw threads 51 and is entered into a clamping washer 52. The screw-threaded end of the crank pin enters a T slot 53, in the front face of a revoluble disk plate 54. The overhanging flanges 55 of the T slot serve as a bearing for the contact of the clamping washer 52, so that when the crank pin is turned in the proper direction the clamping washer will be drawn against the overhanging flanges of the T slot, the flange collar meanwhile overlying the slotted outer face of the revoluble disk, which arrangement serves to rigidly clamp and hold the crank pin at any suitable point with respect to the center of the revoluble disk. The crank pin is provided, at its outer end, with a recess or slot 56, which permits a suitable tool to be entered thereinto.

The revoluble disk plate is provided, on its rear face, with a hub socket 57, which receives the forward end of a power shaft 58, which shaft has loosely mounted thereon a cone pulley 59, provided with a hub 60, having in its rear end clutch recesses 61, which are adapted to coöperate with clutch lugs 62

on the forward end of a slidably mounted clutch collar 63, which is keyed or otherwise secured to the shaft 58. The clutch collar terminates in a grooved clutch head 64, which is adapted to receive a clutch yoke 65 of the usual character, mounted upon a slideable rod 66, which latter is actuated by means of a pivoted handle 67. It will be understood that the clutch mechanism can be modified if desired. The shaft is journaled within forward and rear journal bearings 68 and 69, which are secured to a connecting plate 70, which latter rests upon the bed plate of the machine.

In use, when it is desired to insert a file in position, the upper arm 34 is swung to one side of the hole 71 in the center of the table, which permits a file to be dropped into the socket afforded therefor within the socket block. The file thus inserted can be adjusted to proper position by means of the upper and lower thumb screws, which serve to bring the acting face of the file into exact register with the work, so that as the file is reciprocated it will contact the work evenly at all points of travel. With the file thus positioned and adjusted, the upper arm 34 can be swung back into position for the head 38 to receive the upper end of the file, and the rod 36, being extensible, permits a proper adjustment of the clamping mechanism for the upper end of the file.

When the file has been properly positioned and clamped, the clutch will be thrown to impart power from the constantly rotating cone pulley wheel to the shaft, which revolves the slotted disk. The revolution of the disk causes the transversely reciprocating block to move back and forth within the transverse guideways provided therefor, and likewise causes the vertically reciprocating frame to move up and down, which imparts a reciprocating movement to the file. The power transmission mechanism is one which economizes space to a very marked degree, in that the rearwardly extending arm 31, which supports the vertical rod 33, can be located at a position which allows a bare clearance between the arm and the slotted disk wheel, which arrangement would not be feasible in case a piston rod or similar reciprocating mechanism were employed. The arrangement of the crank pin is one which permits the throw or pitch of the reciprocating mechanism to be varied to any desired extent; and the power transmission mechanism, as a whole, is one which is smooth and certain in its operation and imparts a perfect line movement to the file, which thus serves to abrade the work evenly during all points of its travel. The clutch mechanism is so located and arranged that the device will always be under instantaneous control of the operator, which peculiarly fits the device for use as a bench appliance.

What I regard as new and desire to secure by Letters Patent is:

1. In a filing machine, the combination of reciprocating clamping mechanism adapted to engage both ends of the file, the clamp for the tang comprising a socket member provided with a recess therein, a tilting block pivoted within said recess and having its axis at right angles to the longitudinal dimension of the file tang, a plurality of adjusting screws located on opposite sides of said axis and adapted to bear against the tang of the file, and means for reciprocating the clamping mechanism as a whole, substantially as described. 45
2. In a filing machine, the combination of clamping mechanism adapted to engage both ends of the file, the tang clamping mechanism comprising a socket member provided with a recess therein, a tilting block doubly beveled to an edge on its rear face, such edge bearing against the inner wall of the recess, trunnions for pivoting the block within the recess, the axis of the block being at right angles with respect to the longitudinal dimension of the tang, adjusting screws bearing against the tang on opposite sides of the axis of the block, and means for reciprocating the clamping mechanism, substantially as described. 50
3. In a filing machine, the combination of clamping mechanism adapted to engage both ends of the file, the tang clamping mechanism comprising a socket member provided with a recess therein, a tilting block doubly beveled to an edge on its rear face, such edge bearing against the inner wall of the recess, means for pivoting the block with the recess in a position to have its axis at right angles to the longitudinal dimension of the tang, a plate overlying the recess, adjusting screws entered through said plate 55
4. In a filing machine, the combination of vertical guideways supporting a table thereon, file clamping mechanism slidably mounted within said vertical guideways and comprising a socket adapted to engage the tang of a file, an L bracket extending to the rear of the table, an adjustable arm forwardly extending from the bracket and engaging the upper end of the file, a transverse guideway connected with the file clamping mechanism, and a rotatably mounted member provided with a crank pin entered into the transverse guideway, said crank pin adapted to revolve beneath the L shaped bracket, 60 substantially as described. 55
5. In a filing machine, the combination of vertical guideways having a table mounted thereon, file clamping mechanism slidably mounted within said guideways and comprising a socket below the table adapted to receive and clamp the tang of a file, an L shaped bracket connected with said socket and extending to the rear of and above the table, and an adjustable forwardly extending arm adapted to engage the upper end of the file, a transverse guideway connected with the clamping mechanism below the tang socket, a block slidably mounted within said transverse guideway, a member rotatably mounted beneath the L shaped bracket and provided with an adjustable crank pin entered into the slideable block, and means for rotating said crank supporting member, substantially as described. 65
